CLAIM

The ornamental design for a joystick for a computing input device, as shown and described.

DESCRIPTION

FIG. 1 is a front perspective view of a joystick for a computing input device showing our new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a second bottom perspective view thereof;

FIG. 10 is a front perspective view of the joystick for a computing input device of FIGS. 1-9 shown without disclaimed regions;

FIG. 11 is a bottom perspective view thereof;

FIG. 12 is a front view thereof;

FIG. 13 is a rear view thereof;

FIG. 14 is a right side view thereof;

FIG. 15 is a left side view thereof;

FIG. 16 is a top view thereof;

FIG. 17 is a bottom view thereof; and,

FIG. 18 is a second bottom perspective view thereof.

The broken lines depict portions of the joystick for a computing input device that form no part of the claimed design.
